UNITED STATES PATENT OFFICE.

AUGUST DLOUHY, OF WALLINGFORD, CONNECTICUT, ASSIGNOR TO H. L. JUDD COMPANY, INC., OF WALLINGFORD, CONNECTICUT, A CORPORATION OF DELAWARE.

DESIGN FOR A DRAPERY-POLE END.

Application filed May 2, 1928. Serial No. 26,535. Term of patent 3½ years.

To all whom it may concern:

Be it known that I, AUGUST DLOUHY, a citizen of the United States, residing at Wallingford, in the county of New Haven and State of Connecticut, have invented a new, original, and ornamental Design for a Drapery-Pole End, of which the following is a specification, reference being had to the

accompanying drawing, forming part thereof.

The figure is a front elevation of a drapery pole end, showing my new design.

I claim:

The ornamental design for a drapery pole end, as shown.

AUGUST DLOUHY.
